INVENTOR
Walter L. Tyler

United States Patent Office.

WALTER L. TYLER, OF BRISTOL, CONNECTICUT, ASSIGNOR TO THE E. N. WELCH MANUFACTURING COMPANY, OF SAME PLACE.

Design No. 4,912, dated May 16, 1871.

DESIGN FOR A CLOCK-CASE.

The Schedule referred to in these Letters Patent and making part of the same.

I, WALTER L. TYLER, of Bristol, county of Hartford and State of Connecticut, have invented and produced a new and original Design for a Clock-Case, of which the following is a specification.

In the accompanying drawing—

Figure 1 is a front elevation of my design, and

Figure 2 is a side elevation of the same.

The case is of circular form and is provided with the usual round metallic sash A.

B C are the several laminae of dark and light woods.

The sides of the case are flaring, so that the several laminae B C may be seen when the case is viewed directly from the front

The edges of each of the laminae B C are slightly rounded, thus corrugating the flaring sides, as shown in fig. 2.

The whole is formed and combined as shown and described to produce a new design for a clock-case.

I claim as my invention—

The design for a clock-case, substantially as shown and described.

WALTER L. TYLER.
